UNITED STATES PATENT OFFICE.

JOSEPH HAUK, OF SHOREWOOD, WISCONSIN, ASSIGNOR, BY DIRECT AND MESNE ASSIGNMENTS, TO STANDARD UTILITIES CORPORATION, OF MILWAUKEE, WISCONSIN, A CORPORATION OF WISCONSIN.

DISHWASHING MACHINE.

Application filed September 22, 1920. Serial No. 411,932.

To all whom it may concern:

Be it known that I, JOSEPH HAUK, a citizen of the United States, and resident of Shorewood, county of Milwaukee, and State of Wisconsin, have invented new and useful Improvements in Dishwashing Machines, of which the following is a description, reference being had to the accompanying drawings, which are a part of this 10 specification.

The invention relates to dish washing machines.

One of the objects of the invention is to provide a dish washing machine in which 15 the dishes are carried in a rotating basket and subjected to one or more sprays of cleansing fluid.

A further object of the invention is to provide a machine in which the dishes in a 20 rotating basket are subjected to sprays of water or other cleansing fluid from above and below them.

A further object of the invention is to provide means for alternately introducing 25 soapy and clear water to the pipe or pipes supplying the nozzle or nozzles of the machine.

A further object of the invention is to provide a motor driven dish washing machine 30 in which the motor is automatically stopped after a predetermined period.

A further object of the invention is to provide a dish washing machine having a 35 rotating disc-carrying basket and a rotating washing nozzle for directing a cleansing spray against the dishes in the basket.

In the drawings: Fig. 1 is a plan view of the machine, parts being broken away; Fig. 2 is a section taken on the line 40 2-2 of Fig. 1; Fig. 3 is a section taken on the line 3-3 of Fig. 2; Fig. 4 is a detail view taken as indicated by 4-4 on Fig. 2; Fig. 5 is a section taken on the line 5-5 of Fig. 3; Fig. 6 is a section taken on the 45 line 6-6 of Fig. 5; Fig. 7 is a detail view of the switch.

In the drawings the numeral 8 designates a receptacle supported on legs 9 and provided with a centrally disposed bearing 10 50 in which an upright shaft 11 is journalled, said shaft being secured at its upper end upon the hub 12 of a gear 13 which hub supports a dish-carrying basket 14 within the receptacle. The lower end of the shaft

11 carries a worm wheel 15 meshing with a 55 worm 16 journalled in an arm 17 on the bearing 10. The shaft for the worm 16 carries a pulley 18 connected by a belt 19 to a pulley 20 on the drive shaft 21 of an electric motor 22 mounted on a bracket 23. 60

With this construction the rotation of the motor shaft 21 will, through the driving connections above described, produce a rotation of the basket 14 within the receptacle 8. 65

Mounted upon a frame 24 secured to one of the legs of the machine, are a plurality of valves 25, 26, 27, 28 and 29, each of similar construction. In Fig. 6 I have shown the detail construction of one of these valves and 70 it will be noted that it consists of a casing 30 having an inlet 31, an outlet 32 and a valve 33 controlling passage of fluid from said inlet to said outlet and normally ~~held~~ 75 to its seat by a spring 34. The stem 35 of the valve passes through a stuffing box 36 and projects beyond the casing.

A shaft 37 is journalled in the frame 24 and carries cams 38 which act upon the stems of the valve 26, 27, 28 and 29 to open 80 said valves in predetermined order. This shaft carries a gear 39 meshing with a gear 40 on the rotating shaft 11.

A water supply pipe 41, preferably from a hot water boiler, leads to the inlet of the 85 valve 25. A pipe 42 connects the outlet of valve 25 with the inlets of valves 26, 27, 28 and 29. A pipe 43 connects the outlet of valve 26 with a flexible pipe 44 connected to a pipe 45 carried by a 90 cover 46 hingedly connected to the receptacle 8. The outlet pipe 47 from valve 27 leads to a soaping device 48, which may be of any suitable construction to mix soap with the water, the soapy water being discharged through pipe 49 to the pipe 44. 95

A water-propelled rotating spray nozzle 50 is secured to the end of the pipe 45 and directs the spray of cleansing fluid down upon the dishes in the basket 14. The inlet 100 pipe 51 of the nozzle has a flanged end 52 and carries a cup-shaped cap 53. A nipple 54 is secured to the end of the pipe 45 and has a cup-shaped end in which the end 52 of the pipe 51 is loosely mounted. A cap 55 105 is secured to the nipple 54, the pipe 51 passing through a central bore in said cap. The cap has a cup-shaped upper end and flanged

- 2
- lower end. Ball bearings 56 are seated in raceways between the upper end of the cap 55 and the flanged end of the pipe 51 and ball bearings 57 are seated in raceways between the lower end of said cap 55 and cap 53. The water pressure acts on both sides of the flanged end of the pipe 51 so that the nozzle is practically balanced, the bearings 56 taking the downward pressure and the bearings 57 the upward pressures imparted to the nozzle. The nozzle 50 is balanced by a weight 58 and its discharge end is laterally inclined so that the water pressure revolves it.
- 15 A pipe 59 leads from the outlet of the valve 29 to a fitting 60 provided with a bore 61 and seat 62. A pipe 63 has a flanged end engaging the seat 62 and passes through the bore 61 and carries the cap 64 of a nozzle 65.
- 20 The cap has a gear 66', formed integral with or connected to it, which meshes with the gear 13 so that the nozzle 65 is positively rotated by the rotation of the shaft 11, though it will be understood that a nozzle 25 similar to the upper nozzle which is rotated by the force of the water may be used. The water from the nozzle 65 is directed upwardly against the dishes in the basket 14. A pipe 66 leads from the outlet of the valve 30 28 to a soaping device 67 and the soapy water is conducted through a pipe 68 to the pipe 59.
- The basket 14 is provided with a pin 69 engageable with a gear 70 on a shaft 71.
- 35 The shaft 71 passes through a dial plate 72 having a plurality of recesses 73 at the same distance from the center. An arm 74 is mounted on the shaft 71 and carries a spring-pressed ball 75 adapted to seat in any one 40 of said recesses 73 and hold the gear 70 in predetermined set position until said gear is moved the distance of one tooth during a single revolution of the basket 14 by the engagement of the pin 69 with the gear 70.
- 45 When the arm 74 has been moved to its final position after several revolutions of the basket 14 it strikes the upper end of a switch rod 76 and releases the upper hooked portion 77 of said rod from engagement with a stop 50 78 whereby a spring 79' is free to move the pivoted switch member 79 out of engagement with contact 80, thus opening the motor circuit and stopping the machine.
- The main water valve 25 is actuated by a 55 lever 81 connected by a link 82 with a bell crank lever 83 which is connected by a link 84 with switch member 79. When the motor switch is closed the valve 25 is opened and when the switch is automatically opened in 60 the manner above described the linkage connection above mentioned moves the lever 81 away from the stem of the valve 25 and permits said valve to close.
- While the machine is operating, the valve 65 25 is open and water is supplied from the pipe 42 to the valves 26, 27, 28 and 29. As the shaft 11 rotates the cam shaft 37 is also turned and the cams open the valves 26, 27, 28 and 29 for permitting clear and then soapy water and again clear water being 70 sent to the nozzles 50 and 65. For instance, if the arm 74 is set so that the basket 14 makes twelve revolutions before said arm 74 opens the motor switch, then the opening of the valves 27 and 28 to the nozzles may 75 be so timed as to deliver soapy water during the first three revolutions of the basket, then opening the valves 26 and 29 to deliver clear water during the next three revolutions, then again opening valves 27 and 28 to deliver 80 soapy water for the next three and finally a thorough rinsing with clear water with valves 26 and 29 open during the next three revolutions of the basket. During this time the revolving nozzles 50 and 65, which are 85 eccentrically disposed with respect to the axis of the rotation of the basket, direct their sprays in circular paths against the dishes in the basket from above and below while said basket revolves, with the result 90 that all the dishes in the basket are effectively subjected to the action of the cleansing fluid and are washed in a short time. When the washing operation is completed the machine automatically stops itself. 95 Thus the machine does not require attention while running and all that is necessary is to place the dirty dishes in and remove the clean dishes from the basket after the motor stops. The cleansing fluid may be discharged into the usual kitchen sink or drain from an outlet provided in the lower part of the receptacle 8, as will be readily understood.
- I desire it to be understood that this invention is not limited to any specific form or arrangement of parts except in so far as such limitations are specified in the claims.
- What I claim as my invention is:
1. In a dish washing machine, the combination of a revolving dish-carrying basket, of a pair of revolving nozzles eccentrically disposed with respect to the axis of rotation of said basket and above and below the same and directing washing fluid upon the dishes in said basket.
  2. In a dish washing machine, the combination of a revolving washing nozzle, means for alternately supplying soapy and clear water to said nozzle, a control valve 110 for said supplying means, a revolving dish-carrying basket, means for driving said basket, and means for automatically stopping said driving means and closing said control valve after a predetermined number of revolutions of said basket.
  3. In a dish washing machine, the combination of a revolving dish-carrying basket, a revolving washing nozzle directing washing fluid upon the dishes in said basket,
- 100 115 120 125 130

means for supplying washing fluid to said nozzle including a control valve, means for driving said basket, and means for automatically stopping said driving means and 5 closing said control valve after a predetermined number of revolutions of said basket.

4. In a dish washing machine, the combination of a receptacle having a movable cover, a dish-carrying basket mounted in 10 said receptacle, means for rotating said basket, a rotating nozzle carried by the cover and eccentrically disposed with respect to the axis of rotation of said basket and directing a stream of washing fluid upon the 15 dishes in said basket, a rotating nozzle carried by the bottom of the receptacle and eccentrically disposed with respect to the axis of rotation of said basket and directing a stream of washing fluid upon the dishes in 20 said basket, and means for supplying said nozzles with washing fluid.

5. In a dish washing machine, the combination of a receptacle having a movable cover, a dish-carrying basket mounted in 25 said receptacle, means for rotating said bas-

ket, a rotating nozzle carried by the cover and eccentrically disposed with respect to the axis of rotation of said basket and directing washing fluid upon the dishes in said basket, a rotating nozzle disposed beneath 30 said basket and eccentric to the axis of rotation thereof and directing washing fluid upon the dishes in said basket, and means for supplying said nozzles with washing fluid.

6. In a dish washing machine, the combination of an electric motor, a dish-carrying basket, a revolving nozzle directing washing fluid upon the dishes in said basket, distributor valves, piping connecting said 40 nozzle with said valves, a soaping device included in the piping from one of said valves, a water supply pipe, a control valve in said pipe, piping connecting said control valve with said distributor valves, and 45 means actuated by the motor for operating said distributor valves.

In testimony whereof, I affix my signature.

JOSEPH HAUK.
